MAGNETIC RECORDING AND REPRODUCING ATTACHMENT FOR A PHONOGRAPH

Alec Tutchings, Friars Cliff, Christchurch, England, assignor to W. H. Sanders (Electronics) Limited, Stevenage, England, a British company

Application June 4, 1959, Serial No. 56,200

Term of patent 14 years

(Cl. D26—14)

Fig. 1.

Fig. 3.

Fig. 4.

Fig. 1 is a top plan view of a magnetic recording and reproducing attachment for a phonograph, showing my new design;

Fig. 2 is a top perspective view;

Fig. 3 is a bottom plan view; and

Fig. 4 is a side elevational view thereof.

The broken line showings of tape reels and tape in Fig. 1 are for illustrative purposes only.

I claim:

The ornamental design for a magnetic recording and reproducing attachment for a phonograph, as shown and described.
